HAMMOCK

Salvatore A. Lo Vico, Hollis, N. Y.

Application December 23, 1953, Serial No. 399,981

2 Claims. (Cl. 5—122)

My present invention relates to hammocks and has for its main object the provision of improved means for either two-point or three-point suspension of the hammock body.

In conventional hammocks, an elongated body of fabric of generally rectangular configuration is supported at its extremities by strands or clews which are attached to the fabric and looped through a pair of anchor rings (often referred to as "D-rings") at one end and through a single such ring at the other end of the hammock (three-point mounting), or through a single ring at each end (two-point mounting). The strands of each set are spread out, for the purpose of stress distribution, over a triangular area with its apex at the respective anchor ring and with its base at one of the narrow, transverse edges of the fabric; thus, most of the strands extend at an angle to one another and to the main dimension of the hammock, whereby a change in stress direction occurs at the very point where each clew is attached to the fabric. This condition may cause detachment of the outermost strands, which enclose the sharpest angle with the fabric edge and which are subject to the severest stresses (particularly when the user gets on and off the hammock), followed by progressive overloading of the remaining strands and eventual failure of the entire suspension. To guard against this eventuality, hammocks of this description are often provided with a large multiplicity of strands which render them unsightly and lead to entanglements during transportation or storage.

A more particular object of my present invention, accordingly, is the provision of means for clewlessly suspending the fabric body of a hammock so as to avoid the disadvantages set out above.

According to my invention, I provide each end of a rectangular strip of fabric or other sheet material, serving as the hammock body, with an integral, at least roughly trapezoidal extension and fastening means adjacent the shorter transverse edge of the trapezoid. The fastening means may comprise the usual, roughly triangular anchor rings traversed by straps which extend from said shorter edge. An important feature of my invention resides in the mounting of each ring at a point located substantially in line with either or both of the inclined edges of the trapezoid, whereby the principal stresses of suspension will be absorbed by these edges which may be suitably reinforced by webbing. The webbing may, in fact, be integral with the strap which is looped through a respective anchor ring, the strap being thus attached to the fabric over substantially the full depth of its trapezoidal end portion. Moreover, the suspension is strengthened by the fact that the fabric body itself extends beyond the point where the fastening means begin to exert stresses at an acute angle to the longitudinal direction of the fabric. Also, the hammock thus produced comprises only a minimum number of essential parts, namely, a one-piece body of sheet material and simple means for attaching a set of rings or the like close to the edges

2

thereof, hence it may be manufactured at relatively low cost.

The invention will be better understood from the following detailed description of certain representative embodiments, reference being had to the accompanying drawing in which:

Fig. 1 is a perspective view of a hammock according to the invention, mounted ready for use on a supporting frame;

Fig. 2 is a bottom view of the hammock proper, in outstretched condition; and

Fig. 3 is a fragmentary bottom view of a modified hammock according to the invention.

Fig. 1 shows a hammock 10 suspended between nearly upright ends of a supporting frame 11 of conventional design. Attached to this frame by means of hooks 12a, 12b, 12c are three anchor rings 13a, 13b, 13c, respectively, the last-mentioned ring being connected with its hook by means of a chain 14.

The hammock 10 comprises a rectangular main body portion 15, framed by marginal strips 16, 17 and transverse strips 18, 19, as well as a pair of trapezoidal extensions 20 and 21. Extension 20 is provided with a pair of V-shaped straps 22a, 22b each defining a triangle with part of strip 18; extension 21 is similarly provided with a V-shaped strap 22c defining a triangle with strip 19. Strap 22a extends from strip 18 along one of the inclined edges of trapezoidal portion 20 and a short distance beyond that portion, traverses the ring 13a and returns to the center of strip 18; strap 22b similarly extends along the other inclined edge of portion 20, traverses ring 13b and returns to the junction of strap 22a and strip 18. Strap 22c, joining strip 19 at its ends, extends along both inclined edges of trapezoidal portion 21 and slightly beyond that portion to pass through ring 13c.

The straps 22a—22c as well as the strip members 16—19 may consist of similar pieces of strong webbing stitched to the fabric of body 15, 20, 21 along the entire area of contact therewith, as indicated in dotted lines in Fig. 2. It will be understood that straps 22a, 22b may be integral with each other, and/or with strip 18 or strips 16, 17, and that strap 22c may similarly be integral with strip 19 or with strips 16, 17. The marginal strips such as 16, 17 may, of course, extend along both surfaces of the hammock body if desired; they may also serve as fastening means for tassels 23 or similar adornments. Transverse strips 18, 19 act as retaining means for stiffening rods 25, preferably of spring steel, serving to maintain the flat shape of the hammock body.

An auxiliary strap 24 is shown to extend along the center of the large trapezoidal extension 21 and to be looped through ring 13c to give additional support. The modified hammock 110 of Fig. 3 comprises a central body portion 115 provided with two roughly trapezoidal extensions of which only the left-hand extension 120 has been shown. This extension terminates in two integral straps 122a, 122b designed to be bent over and stitched to the underlying fabric, as shown for strap 122a, to engage an anchor member such as ring 113a. The entire hammock body, including the strap portions 122a, 122b, is shown lined with webbing 116.

It will be noted that the roughly trapezoidal extension 120 forms a saddle between straps 122a, 122b to avoid sharp angles at the inner edges of these straps. This saddle may, of course, be deepened until the end portion 120 is split into two roughly triangular but essentially trapezoidal sections each with its own anchor ring, comparable to the sections defined by webbing 22a, 22b in Fig. 2. It will also be understood that the right-hand end of hammock 110 is of substantially the same configuration as end portion 21 in Fig. 2, i. e. nearly triangular,

70

and terminates in a single central strap such as 122a, 122b.

The hammocks 10, 110 shown in the drawing, adapted for three-point mounting, may of course be modified for two-point suspension by replacing the extension 20 or 120 with a trapezoidal portion similar to extension 21. This and other modifications will be readily apparent to persons skilled in the art and are deemed to come within the scope of the invention as defined in the appended claims.

I claim:

1. A hammock comprising a rectangular body of sheet material having a pair of at least roughly trapezoidal end portions integral with said body, first and second anchor means each including at least one ring adjacent a respective end portion, two continuous strip members engaging said rings and extending between said first and second anchor means on opposite sides of said body, said strip members lining the edges of said body and the inclined flanks of said trapezoidal end portions, a pair of transverse strips connected at their ends with said continuous strip members and extending along the junction lines between said body and said end portions, and auxiliary strip means connected with said continuous strip members

and extending from said rings across the respective end portions to the center of the corresponding transverse strip.

2. A hammock according to claim 1, wherein one of said end portions has an outer transverse edge longer than the corresponding edge of the other end portion, said anchor means comprising a pair of rings at said one end portion and a single ring at said other end portion.
